GEORGE F. DE WEIN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CRUSHER-MANTLE.

1,154,100.

Specification of Letters Patent. Patented Sept. 21, 1915.

Application filed December 24, 1913. Serial No. 808,908.

To all whom it may concern:

Be it known that I, GEORGE F. DE WEIN, a citizen of the United States, residing at Milwaukee, in the county of Milwaukee and State of Wisconsin, have invented a certain new and useful Improvement in Crusher-Mantles, of which the following is a specification.

This invention relates to improvements in the construction of sectional crusher mantles, and more specifically to means for automatically tightening or locking the mantle sections to their supporting elements.

An object of the invention is to provide simple and efficient means for automatically and simultaneously locking a plurality of associated mantle sections to each other and to their supporting elements.

The invention herein disclosed is an improvement in the device disclosed in Patent No. 1,066,277, dated July 1, 1913, and consists essentially in providing T-shaped interlocking extensions and projections at the adjacent ends of the mantle sections for automatically producing a locking pull upon each section at more than one portion thereof, and for preventing axial separation of the sections during the locking movement of one of the sections upon its supporting element. In the patented device, the locking projections on each of the sections are diametrically oppositely disposed and extend in the same direction relative to a diameter, so that upon relative rotation of the sections the adjacent locking projections on one side of the mantle will tend to interlock, while the adjacent locking projections on the other side of the mantle will tend to recede from each other and to unlock.

With the present invention, diametrically opposite locking projections extending in opposite directions relative to a diameter are provided, these projections being arranged in pairs and so disposed that a uniform locking pull upon each section is procured irrespective of the direction of the relative rotation of the sections upon their supporting elements.

The present invention furthermore involves a simple formation of the ends of the sections whereby the cost of construction of these sections is reduced to a minimum. While the present disclosure shows a crusher mantle comprising only two sections, it

should be understood that the invention is generally applicable to devices in which any number of sections are used.

A clear conception of an embodiment of the invention may be had by referring to the drawing accompanying and forming a part of this specification in which like reference characters designate the same or similar parts in the various views.

Figure 1 is a front view of a gyratory crusher head provided with a sectional mantle and showing a fragment of the supporting shaft. Fig. 2 is a transverse vertical section through a gyratory crusher head provided with a sectional mantle and showing a fragment of the supporting shaft, the section being taken along the line II—II of Fig. 3 looking in the direction of the arrows. Fig. 3 is a bottom view of the gyratory crusher head and shaft.

The gyratory crusher head consists of a center piece or core 2 having a central tapered bore which fits over a correspondingly tapered portion of the main crusher shaft 1. The core 2 is fixed to the shaft 1 by means of keys 3 which are fitted into keyways 4 formed in the tapered portion of the shaft 1. The core 2 is forced down upon the tapered portion of the shaft 1 by means of a jam nut 7 which coacts with screw-threads 5 formed on the shaft 1, and with the upper portion of the core 2. The jam nut 7 is locked into place by means of a lock nut 6 coacting therewith and also coacting with screw-threads 5 formed on the shaft 1.

The outer surface of the core 2 is formed tapered or conical in shape and is provided with mantle sections, 8, 9, having central conical bores which fit the taper of the outer surface of the core 2. The lower mantle section 9 is provided at its lower and larger end with inwardly projecting diametrically opposite locking lugs 10 having upper helical surfaces. The lower end of the core 2 is provided with helical locking surfaces 12 which, with the mantle section 9 in normal position upon the core 2, coact with the upper helical surfaces of the lugs 10. The lower portion of the core 2 is also provided with vertical diametrically opposite recesses 11 through which the locking lugs 10 are free to pass during the assembling of the crusher head. The locking lugs 10 and helical surfaces 12 provide a suitable locking

device for the lower mantle section 9 for relative rotation of the section 9 upon the core 2 in either direction, this device being substantially analogous to that disclosed in 5 Patent No. 848,782, dated Apr. 2, 1907.

The upper extremity of the lower section 9 is provided with diametrically opposite upwardly projecting T-shaped extensions having locking projections 14, 15, 16, 17, extending laterally therefrom. The pairs of 10 projections 14, 17 and 15, 16 are diametrically opposite and extend in opposite directions relative to their common diameters. The major portion of the upper end surface 15 13 of the lower section 9 is formed as a plane surface 13 which is preferably made perpendicular to the common axis of the mantle sections and of the crushing head.

The lower end of the upper mantle section 8 is provided with diametrically opposite upwardly extending T-shaped recesses each having a pair of lateral locking projections 18, 19, 20, 21, extending toward each other and partially spanning the recesses. 20 With the mantle assembled, the upper T-shaped extensions of the lower section 9 are disposed within the correspondingly shaped recesses in the lower portion of the upper section 8, while the upper plane surface 13 25 of the major portion of the lower section 9 coacts with a similarly disposed plane surface 13 at the lower end of the upper section 8.

In order to assemble the mantle, the extensions formed on the lower section 9 must first be brought into alignment with the similarly formed recesses on the upper section 8, the axes of the sections being parallel to each other and the sections 8, 9, being staggered, after which relative lateral shifting of the sections 8, 9, will bring them into a position where their axes as well as their corresponding extensions and recesses will coincide. In order to permit ready assembling of the parts in this manner, the recesses in the section 8 are formed slightly larger than the corresponding extensions on section 9, and the sides of the recesses and extensions are formed with parallel straight 45 50 line elements.

With the crushing head assembled and during normal operation of the same, relative rotation of the lower section 9 upon the core 2 will cause the lugs 10 to ride along the surfaces 12 and to thereby firmly lock the lower mantle section upon the tapered outer surface of the core 2 by pulling the mantle section 9 downwardly. This relative rotation and downward movement of the section 9 upon the core 2 will be transmitted through the extensions at the upper end thereof to the upper section 8. If the relative rotation of the section 9 upon the core 2 is in a clockwise direction, looking 60 65 downwardly upon the head, the diametrical

opposite, oppositely disposed projections 14, 17, will move toward the recesses formed above the projections 18, 21, respectively, and will simultaneously tend to pull the upper section 8 down against the outer 70 taper of the core 2 at points on opposite sides of the section 8. If the relative rotation of the section 9 upon the core 2 is in an anti-clockwise direction, the projections 15, 16, will move toward the recesses formed above 75 the projections 19, 20, and will again tend to pull the upper section 8 down against the outer taper of the core 2 at points on opposite sides thereof. It is thus to be noted that irrespective of the direction of relative rotation of the lower mantle section 9, the upper section 8 will simultaneously be pulled down against the taper of the core 2 by means of the projections 14, 15, 16, 17. The fact that these projections are arranged in 80 diametrically opposite oppositely disposed pairs, provides an efficient means for producing a simultaneous locking pull on the section 8 on opposite sides thereof. The formation of the adjacent ends of the sections 8, 9, as plane surfaces 13 which are perpendicular to the axes of the sections, also facilitates construction of the section ends. 90

It should be understood that it is not desired to be limited to the exact details of construction shown and described, for obvious modifications will occur to a person skilled in the art.

It is claimed and desired to secure by Letters Patent,—

1. In a crusher, a mantle comprising a plurality of sections each having diametrically opposite locking projections extending in opposite directions relative to a diameter and formed to tend during operation to 105 draw the sections together.

2. In a crusher, a mantle comprising a plurality of sections each having diametrically opposite locking projections extending in opposite directions relative to a diameter, 110 and the projections on adjacent sections extending in opposite directions relative to each other and formed to tend during operation to draw the sections together.

3. In a crusher, a mantle comprising a 115 plurality of sections, one of said sections having a pair of diametrically opposite T-shaped extensions coacting with similarly formed recesses in the adjacent section and formed to tend during operation to draw the 120 sections together.

4. In a crusher, a mantle comprising a plurality of sections, the adjacent ends of said sections being formed with diametrically opposite coacting T-shaped extensions 125 and recesses for preventing axial separation of said sections and formed to tend during operation to draw the sections together.

5. In a crusher, a mantle comprising a plurality of co-axial sections having parallel 130

plane adjacent end surfaces formed perpendicular to the axis of said sections, the adjacent ends of said sections being formed with diametrically opposite interlocking projections for preventing axial separation of the sections and formed to tend during operation to draw the sections together.

In testimony whereof, the signature of the inventor is affixed hereto in the presence of two witnesses.

G. F. DE WEIN.
